(57) **CLAIM**

The ornamental design for a handle applied to handbag, as shown and described.

DESCRIPTION

FIG. 1 is a perspective view of a handle applied to handbag, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown on the claimed surfaces of the handle represent stitching that forms a part of the claimed design. The broken lines depicting a handbag depict environment and form no part of the claimed design.

1 Claim, 6 Drawing Sheets
